UNITED STATES PATENT OFFICE.

BERNT TENNESON, OF PHILADELPHIA, PENNSYLVANIA; OLEVINE
TENNESON AND WILLIAM H. BAKER EXECUTORS OF SAID
BERNT TENNESON, DECEASED.

BOAT.

No. 828,072.

Specification of Letters Patent.

Patented Aug. 7, 1906.

Application filed February 3, 1906. Serial No. 299,352.

To all whom it may concern:

Be it known that I, BERNT TENNESON, a citizen of the United States, and a resident of the city and county of Philadelphia, State of Pennsylvania, have invented certain new and useful Improvements in Boats, of which the following is a specification.

My invention relates to improvements in folding boats, and more particularly to improvements in that class of folding boats having an inner part or frame constructed of hinged sections adapted to fold lengthwise and an outer covering of canvas or other suitable waterproof flexible material; and the objects of my invention are to furnish an improved means for securing the upper sides of the canvas cover to the wooden inner part of the boat, to furnish an improved means for detachably securing the thwarts to the boat, and to furnish an improved means for securing in place a detachable square stern.

In the accompanying drawings, forming part of this specification, and in which similar letters of reference indicate similar parts throughout the several views, Figure 1 is a top plan view of my improved folding boat; Fig. 2, a section of Fig. 1 on line A A; Fig. 3, an enlarged section of part of one side of the boat, showing the means for attaching one end of a thwart thereto; Fig. 4, an enlarged section of part of the other side of the boat, showing the means for securing the other end of the thwart; Fig. 5, a perspective view of keeper for the end of the thwart shown in Fig. 3; Fig. 6, a perspective view of keeper for the end of thwart shown in Fig. 4; Figs. 7 and 8, enlarged views, partly in section, of opposite ends of a thwart; Fig. 9, a perspective view, looking toward the stern, of the square stern and means for securing it to the sides of the boat; Fig. 10, a plan view of a modified thwart-securing means, the thwart being shown in full, while parts of opposite sides of the boat and the keepers are shown in section; Fig. 11, a longitudinal section of part of the stern end of the boat, showing means for securing square stern; Fig. 12, a transverse section of the boat when folded; Fig. 13, a section of upper part of canvas cover, showing hole through which oar-lock plate may be passed.

a is the keel, *b* the bottom, and *c* the sides, of the boat. These parts are prefer-

ably made of wood and are hinged together, so that the sides *c* may be folded over on top 55 of the bottoms *b* and the latter moved up at right angles with the keel, as shown in Fig. 12, in order that the boat may be reduced to the smallest size for either stowing or shipping. 60

The manner of constructing the keel, bottom, and sides of the boat, as well as the means for securing these several parts together, being old and well known, I make no claim thereto, nor do I deem it necessary at 65 this time to more fully describe them.

d is a canvas cover, which not only insures the boat being water-tight, but which also serves to protect the wooden part of the boat from injury when in use or when being 70 shipped. At one or both ends the cover passes over the top of the boat, and in order that it may be readily put in place or removed it is secured at this point by a lacing *e*, Fig. 1. The cover with the laced end or 75 ends is in itself old; but my method of securing it in place along the gunwales is new. At several places near the upper end of the cover I cut holes *f*, Fig. 13, and pass through these holes a corresponding projection carried by 80 the upper inner sides of the boat. Then through the projection I pass a suitable key to keep the cover from leaving the projection. The projections that I preferably use for this purpose are the sockets *g*, which 85 carry the oar-locks *h*, the oar-lock serving as the pin to prevent the withdrawal of the canvas from the sockets.

Boats of the class described are held in their open position by the thwarts alone, and hence it is desirable that a thwart-fastening be used which will not be liable to come unfastened. To this end I secure upon opposite sides of the upper portions *c c* of the boat keepers *i j*. (Best shown the former in Fig. 95 5 and the latter in Fig. 6.) The keeper *i* is furnished with a slot *k*, and the end of the thwart *l*, which rests upon this keeper, is furnished with a hook *m*, Fig. 7, which is adapted to pass in the slot *k* and engage the metal 100 to the rear of the slot. The opposite end of the thwart *l* carries upon its under side a spring-operated bolt *n*, which when this end of the thwart rests upon the keeper *j* is adapted to engage the under side thereof. This 105 end of the thwart also carries depending pro-

jections *o*, which are adapted to enter corresponding holes *p* in the keeper *j*.

The hook *m* when in engagement with the keeper *i* prevents one end of the thwart from being lifted or drawn away from this keeper, while the projections *p* and the bolt *n* serve the same purpose for the other end of the thwart; but by retracting bolt *n* the end of the thwart carrying the bolt may be lifted 10 clear of the keeper *j*, and a further lifting of this end will place the hook *m* in position to be withdrawn from keeper *i*.

A bow-thwart is shown in Fig. 10. In this case the keepers *r s*, secured to the sides of 15 the boat, are furnished each with a horizontal slot *t*. The slot *t* in the keeper *r* is open at the forward end and closed at the after end. The slot *t* in the keeper *s* is open at the after end and closed at the forward end. The 20 thwart is put in place by entering diagonal corners of opposite sides in the open ends of the slots and forcing it in place. At the forward end of the boat spreading of the sides is prevented by the laced top of the cover, (shown in Fig. 1,) and hence other fastenings 25 are not necessary.

The square stern *u* of the boat is shown in Figs. 1, 9, and 11. At the central part of its inner lower end the stern *u* carries a hook-shaped casting *v*, and at the rear end of the 30 top of the keel *a* is carried a mating casting *w*. By moving the stern to either side the casting *v* may be disengaged from casting *w*; but when these castings are in engagement they 35 prevent any upward movement of the stern. *x* represents loose butt-hinges one side of which are secured to the upper sides *c* of the boat and the other side of which are secured to the stern *u*. When the pins *y* of these hinges are 40 in place and the castings *v w* in engagement,

the stern *u* is securely locked to the sides and keel of the boat. If the pins *y* be withdrawn and the canvas cover be removed from the stern of the boat, the stern is in condition to be moved so as to unlock the castings *v w*, 45 after which the thwarts may be removed and the boat collapsed, as shown in Fig. 12.

Having thus described my invention, I claim as new and desire to secure by Letters Patent—

1. In a boat, in combination, a collapsible frame, projecting rowlock-sockets carried by the upper inner part of said frame, and a canvas cover the upper edges of which are furnished with holes adapted to pass over the 55 rowlock-sockets.

2. In a boat, in combination, a frame collapsible lengthwise, keepers placed opposite one another, one on each of the inner sides of the boat, a thwart, a hook carried by one end 60 of the thwart adapted to engage one of said keepers, a spring-bolt carried by the other end of the thwart adapted to engage the under side of the other keeper, and projections carried by the latter end of the thwart adapted to pass down through corresponding holes in said latter keeper.

3. In a boat, in combination, a frame collapsible lengthwise, a square stern, mating hooks, one carried by the keel of the boat and 70 the other by said stern, adapted to secure said stern and keel together, and loose butt-hinges one of the sides of which are secured to said stern and the other to the sides of the boat, adapted to secure said stern and sides 75 together.

BERNT TENNESON.
